UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SHEET-DELIVERY MECHANISM FOR PRINTING-PRESSES.

1,353,509.

Specification of Letters Patent. Patented Sept. 21, 1920.

Application filed October 30, 1918. Serial No. 260,361.

To all whom it may concern:

Be it known that I, HOWARD M. BARBER, a citizen of the United States, and resident of Stonington, in the county of New London and State of Connecticut, have invented a new and useful Improvement in Sheet-Delivery Mechanism for Printing-Presses, of which the following is a specification.

The object of my invention is to provide novel means for insuring the rapid delivery of sheets from an impression cylinder, especially an impression cylinder having a plurality of impression surfaces, and comprises a fly and a delivery carrier, the delivery carrier serving to collect the sheets from the impression cylinder and deliver them onto the fly.

My invention more particularly includes a combined sheet collecting and delivery cylinder having alined sets of grippers and means for operating one set of grippers every revolution of the carrier at both the taking and delivery points and for operating the other set of grippers every second revolution of the carrier at the taking and delivery points, whereby a collection of two sheets is obtained, thus giving the fly ample time to perform its functions even at a very rapid operation of the press.

In the accompanying drawings.

Figure 1 is a detail view partly in side elevation and partly in section of a sheet feeding carrier, the impression cylinder, delivery carrier and fly.

Fig. 2 is a detail view of the cams and gears at the far side of the press.

Fig. 3 is a plan view of the delivery carrier.

Fig. 4 is a detail front view of the same on a larger scale.

Fig. 5 is a detail section on the same scale as Fig. 4 in the plane of the line V—V of Fig. 3, and

Fig. 6 is a detail section on a similar scale in the plane of the line VI—VI of Fig. 3.

The sheet feeding carrier in the present instance, a reel 1 has a set of grippers 2. The impression cylinder 3, is shown as having a plurality of impression surfaces 4 and sets of grippers 5 arranged to take successive sheets from the set of grippers 2. The combined sheet collecting and delivery carrier, in the present instance a reel 6, is shown as having two alined sets of grippers 7 and 8. The fly 9 is arranged to deliver the collected sheets from the delivery carrier 6 to a table

or other point not shown herein, it being understood that any suitable means of well known or approved construction may be utilized to operate the fly every second revolution of the delivery carrier. 60

The means which I have designed to operate the set of grippers 7 at the taking and delivery points every revolution of the delivery carrier and the set of grippers 8 every second revolution at the taking and delivery points, is constructed, arranged and operated as follows:

Each gripper 7 is loosely mounted on the rocking gripper shaft 10 and it is held yieldingly closed by means of a spring 11 coiled around the gripper shaft one end of the spring pressing on the grippers and the other end anchored in a collar fixed to the shaft. The gripper 7 has a stud 12 engaged by an arm 13 fixed to a rock shaft 14 which rock shaft has an operating arm 15 provided with a stud or roller 16 in position to be engaged by the stationary cam 17 at the taking point and a stationary cam 18 at the delivery point. The grippers 8 are fixed to the gripper shaft 10 which shaft has the usual operating arm 19 provided with a stud or roller 20 arranged to be engaged by a movable cam 21. This cam is provided with an operating arm 22 provided with a stud or roller 23 which travels in a cam groove 24 in a disk 25 driven at one half the speed of the delivery carrier 6 through the gears 26, 27. The spring 28 serves to yieldingly hold 90 the grippers 8 closed as usual.

From the above description it will be seen that the fly is given ample time to perform its functions, without slowing down the press. While I have described the invention in connection with means for collecting two sheets from the impression cylinder it is evident that I do not wish to limit myself to this particular arrangement but contemplate the collection of any number of 100 sheets on the delivery carrier to suit varying conditions.

What I claim is:

1. An impression cylinder having a plurality of impression surfaces, a rotary delivery carrier arranged to take successive sheets directly from the impression cylinder surfaces, to collect said sheets, and a fly for taking the so collected sheets directly from the rotary carrier and deliver them. 105

2. An impression cylinder, a rotary delivery carrier having independently oper-

ated alined sets of grippers arranged to collect sheets from the impression cylinder, a fly for delivering the so collected sheets and means for operating one set of grippers every revolution of the carrier and the other set of grippers every second revolution of the carrier.

3. An impression cylinder, a rotary delivery carrier having independently operated alined sets of grippers arranged to collect sheets from the impression cylinder and deliver the so collected sheets, a rock shaft having arms engaging the grippers of one set and stationary cams for engaging the operating arms of the said rock shaft, a movable cam for engaging the operating arms of the second set of grippers and a cam disk driven from the carrier at half speed for moving the movable cam.

20 4. An impression cylinder, a rotary delivery carrier having independently oper-

ated alined sets of grippers arranged to collect sheets from the impression cylinder, a fly for delivering the so collected sheets, means for operating one set of grippers every revolution of the carrier and means for operating the other set of grippers every second revolution of the carrier, the first named means comprising a rock shaft having arms engaging the grippers of one set, stationary cams for engaging the operating arms of said rock shaft, and the second named means comprising a movable cam for engaging the operating arms of the gripper shaft and a cam disk driven from the carrier at half speed for moving the movable cam.

In testimony that I claim the foregoing as my invention, I have signed my name this twenty-eighth day of October, A. D. 1918.

HOWARD M. BARBER.
